Primary Examiner — Melanie Pellegrini

(57) **CLAIM**

The ornamental design for a bracelet, as shown and described.

DESCRIPTION

1. Bracelet
- 1.1 : Perspective
- 1.2 : Front
- 1.3 : Back
- 1.4 : Right
- 1.5 : Left
- 1.6 : Top
- 1.7 : Bottom
- 1.8 : Perspective
- 1.9 : Perspective

The bracelet has a flexible strap and a clasp comprising two elements connected to the ends of the strap; a first element of the clasp has a shape resembling an H rotated by 90 degrees and has a retaining element that extends vertically between its horizontal wings or crosspieces; the other clasp element has a substantially square C-shaped part from which a horizontal branch extends, the distal end of which is bent into a hook for engaging with the retaining element of the first clasp element.
